UNITED STATES PATENT OFFICE.

EDWARD H. BAUER, OF CHICAGO, ILLINOIS, ASSIGNOR TO SIMPLEX RAILWAY APPLIANCE COMPANY, OF CHICAGO, ILLINOIS, A CORPORATION OF ILLINOIS.

BRAKE-BEAM.

No. 921,344.

Specification of Letters Patent.

Patented May 11, 1909.

Application filed July 7, 1908. Serial No. 442,357.

To all whom it may concern:

Be it known that I, EDWARD H. BAUER, a citizen of the United States, residing at Chicago, in the county of Cook and State of Illinois, have invented certain new and useful improvements in Brake-Beams, of which the following is a specification.

In some railway car-trucks but little room is provided for the accommodation and 10 movements of the brake-beam and its associated heads.

The object of this invention is therefore to so construct the brake-beam and its end sleeves that the latter and the heads carried 15 thereby will project back of the compression-bar of the beam a minimum amount. Ordinarily a channel-bar is used for the compression element or member of the brake-beam truss, its ends, as well as those of the usual 20 coöperating tension-rod, being received in apertures in end sleeves on which the brake-heads are mounted. I have found that by convexing or curving the web and flanges of such a channel-bar at its ends, that is, by 25 pressing them somewhat into a rounded or convex, instead of substantially-rectangular, cross-section, the sleeve with an altered aperture 30 may be placed farther forward on the brake-beam, economizing in the necessary space for the reception of the beam and its 35 heads and their movements.

On the drawing, which forms a part of this specification, I have illustrated the most desirable embodiment of the invention; and, 40 on the drawing,—Figure 1 is a plan view of the end portion of a brake-beam having my improved compression member and sleeve; Fig. 2 is a top plan view of an end portion of the compression-bar; Fig. 3 is a face view or side elevation of the part shown in Fig. 2; Fig. 4 illustrates, on an enlarged scale, the cross-section 45 of the compression-bar at its central portion; Fig. 5 illustrates a cross-section of the same bar near its end; Fig. 6 is a section on line 50 6—6 of Fig. 1; and Fig. 7 illustrates the arrangement of parts and the form of sleeve necessary when the end of the channel compression bar is not rounded as indicated in Fig. 6.

The brake-beam has a channel compression-element or bar 10, the general cross-section of which is indicated in Fig. 4. At 55 its ends, at 11, the web and portions of the parallel flanges of the bar 10 are pressed or rounded into convex form, as shown in Figs.

5 and 6. The brake-beam is also supplied with the usual tension-rod 12, the ends of which and the rounded portions 11 of the compression bar are received, as usual, in apertures of cylindrical sleeves 13, only one 60 of which is indicated on the drawing.

In Fig. 7 I have shown in cross-section the style of sleeve 13^a which it will be necessary to use if the ends of the channel compression-bar 10^a were not rounded, as shown in Fig. 65 6, the position of the rod 12 being the same in each instance. Owing to the fact that by transversely rounding or curving the ends of the channel compression-bar the parts most remote from the center of the tension-rod 12 are brought nearer to the same, the aperture or passage in the sleeve 13 which receives the ends of the tension-rod and compression-bar may be arranged more concentrically, thereby bringing the center of the 70 sleeve farther forward on the brake-beam. This advantage will be readily understood by a comparison of the constructions shown in Figs. 6 and 7, from the latter of which it is obvious that, owing to the greater distance 75 from the center of the tension-rod 12 to the longitudinal edges 10^b of the channel compression-bar, it is necessary to so arrange the aperture in the sleeve as to leave a considerable portion of the sleeve rearwardly of 80 the web of the compression-bar. It is just this arrangement and disposition of the parts 85 which my improved construction avoids.

It is to be understood that, although I have shown and described a single preferred 90 embodiment of my invention, the invention is nevertheless not limited and restricted to the precise details of construction set forth, because these may be varied within comparatively wide limits without departing from 95 the substance of the invention.

I claim:

1. In a brake-beam, the combination of a compression-bar channel-shaped in cross-section, the ends only of which have their exterior surfaces rounded, a tension-rod, and sleeves fitted over the ends of said compression-bar and tension-rod securing the same together, substantially as described.

2. In a brake-beam, the combination of a compression-bar channel-shaped in cross-section, comprising a flat central web the opposite longitudinal edges of which are equipped with parallel flanges, said web at the ends of said bar being curved in cross- 105 110 115

section, a tension-rod, and sleeves fitted over the ends of said compression-bar and tension-rod and securing the same together, substantially as described.

5 3. In a brake-beam, the combination of a compression-bar channel-shaped in cross-section, the longitudinal edges of the web of said bar at the ends of the same being round-

ed, a tension rod, and sleeves fitted over the ends of said compression-bar and tension-rod and securing the same together, substantially as described.

EDWARD H. BAUER.
